UNITED STATES PATENT OFFICE

CLAUDE L. POST, OF CHICAGO, ILLINOIS

FEEDING MECHANISM

Application filed January 15, 1930. Serial No. 420,917.

The invention relates to feeding devices for feeding paper stock from a pile or hopper to a machine such as a printing press.

The invention is particularly designed for feeding envelopes, shipping tags and like paper stock to the press.

It is one of the prime objects of the invention to provide a means which is extremely simple in character for successive feeding 10 the stock from a hopper.

It is a further object of the invention to employ one or more rotatable elements located preferably below the hopper having means intermittently movable into the path 15 of travel of the stock, said means including means for frictionally engaging the stock to thereby cause it to be fed from the hopper.

It is another object of the invention to provide means such as that just referred to which 20 provides means for holding the stock in the hopper and intermittently feeding the stock therefrom.

A further object of the invention is to employ a disc rotatable relatively to the open 25 end of the hopper to thereby intermittently present different portions of the disc to the stock to thereby respectively hold the stock within the hopper and feed the stock therefrom.

Another object of the invention is to employ a pair of oppositely rotatable elements 30 having means for frictionally engaging the stock to cause the latter to be fed from the hopper.

Another feature of the invention is to provide oppositely rotatable elements capable 35 of holding the material or the stock within the hopper and intermittently feeding the stock therefrom having means for frictionally engaging the stock to cause it to be fed from the hopper, the frictional means being rotatable in synchronism with each other into and out of the path of movement of the stock 40 contained in the hopper to thereby feed the

stock from the hopper to a machine such as a printing press.

Another feature of the invention is to provide means which may be regulated to insure the feeding of a single article from the hopper, this means being adjustable. 50

Another object of the invention is to provide a device such as that above referred to having combined therewith an agitator or jogger which is arranged and designed so as 55 to cooperate with other elements of the structure to insure against feeding more than a single piece of stock from the hopper.

The invention has these and other objects, all of which will be more readily understood 60 when read in conjunction with the accompanying drawings which illustrate one embodiment of which the invention is susceptible, it being evident that changes and modifications may be resorted to without departing 65 from the spirit of the appended claims forming a part hereof.

In the drawings, Fig. 1 is a side elevation of a printing press having the feeding means associated therewith. 70

Fig. 2 is a plan view of the feeding mechanism;

Fig. 3 is a section taken on line 3—3 of Fig. 2;

Fig. 4 is a view, partially in section, taken 75 on line 4—4 of Fig. 3;

Fig. 5 is a section taken on line 5—5 of Fig. 4; and

Fig. 6 is a sectional view of a fragment of 80 a feeding disc employed in the structure.

In the embodiment of the invention illustrated in the drawings, the feeding mechanism generally designated A is associated with a printing press generally designated B. The latter includes the usual ink fountain 10, ink roller 11 and the ink distributing rollers 12. A printing press of the type illustrated includes a rotatable platen and other elements forming no part of the present invention and, therefore, will not be ex- 85 90

plained in detail. The printing press structure generally designated B includes a shaft 13 from which power is taken to operate the feeding mechanism generally designated A, 5 the power being derived from the shaft 13 through the medium of a chain or belt 14 which extends to and causes rotation of the sprocket 15 secured to the shaft 16. The shaft 16 has a gear 17 which meshes with a 10 similar gear 18. The gear 18 is mounted upon a shaft 19 which is journaled at its opposite ends in side frame members 20—20. This shaft 19 carries a feed roller 21 which cooperates with a feed roller 22 provided to 15 assist in conveying the material or stock fed from the hopper to the printing press after it has been extracted from the hopper. The roller 22 is mounted upon a shaft 23 also journaled in side frames 20—20 as clearly 20 shown in Fig. 4.

It may be here stated that the side frames 20—20 are connected in any convenient manner with a supplemental frame which is secured to some suitable portion of the main 25 frame of the printing press generally designated B. A pinion 25 is mounted on a vertical shaft 26, the latter being journaled in a transverse portion 27 of the supplemental frame of the feeding mechanism generally 30 designated A. The shaft 26 carries a sprocket 28 over which is trained a sprocket chain 29, the sprocket chain 29 being in turn connected with a sprocket 30 secured to the vertical shaft 31, the latter of which is also 35 mounted or journaled in the stationary portion such as 27 of the frame A of the feeding mechanism.

By referring particularly to Figs. 4 and 5, it will be noted that the shaft 31 has a gear 40 32 mounted thereon which meshes with a gear 33, the latter of which in turn meshes with a gear 34 which cooperates with a gear 35. The shafts 31 and 36 to which the gears 32 and 35 are respectively connected are, as 45 before stated, suitably journaled in the main frame and each of these shafts respectively carry discs designated 37 and 38 which are arranged below the hopper generally designated 39 within which the stock to be fed to 50 the printing press is retained and provide means for feeding the stock from the hopper.

The mechanism, including the gear 18, shaft 19, pinions 24 and 25, sprocket 29 and sprocket 30, the disc 37-38 secured to the 55 shafts 31 and 36 will, by virtue of the gear train including the gears 32 to 35, inclusive, cause said discs to rotate in opposite directions. By referring to Fig. 2, it will be noted that each of the discs 37 and 38 extend into 60 the path of travel of the material confined in the hopper 39 and that each of these discs 37 and 38 are respectively provided with segmental portions respectively designated 40 and 41. These segmental portions 40 and 41 65 are produced of some preferably resilient

material which will frictionally engage the lowermost article in the hopper and thus cause the material to be fed therefrom to the feed rollers 21 and 22 from which the article is in turn fed to the conveyor generally designated 42 which, in the present instance, includes the conveyor chains 43 and 44. These conveyor chains 43 and 44 are provided with lugs such as 45 (see Fig. 3) which engage an edge of the stock and convey it to the printing elements of the printing press. Each of these segmental portions 40 and 41 are held relatively to the discs 37 and 38 through the agency of a depressed portion 48 provided in each of the discs. These segmental resilient frictional elements 40 and 41 are preferably located to extend from the periphery of each disc toward the center thereof and are preferably of wedge or triangular shape with the vertex located so that it initially engages the stock, and thus prevents the possibility of buckling of the sheet when the resilient elements 40 and 41 initially engage the sheet. It will be evident that since the discs 37 and 38 are arranged relatively to the hopper so that a portion thereof extends inwardly beyond the sides of the hopper, that said discs provide means for maintaining the stock within the hopper during and after functional operation of the segmental portions 40 and 41. It will further be evident that these segmental portions 40 and 41 are disposed and arranged relatively to each other so that they operate in synchronism to extract a sheet from the hopper and that the remaining portion of the discs also act in synchronism to function to hold the material within the hopper.

The hopper generally designated 39 is in the present instance comprised of the two elements 47 and 48 which are supported through the agency of bars or rods 49 connected with the side frames 20—20.

The front of the hopper generally designated 39 is formed by the plate 50 also secured for support to the side frames 20—20. This plate 50 carries an adjustable means 51 which may be regulated relatively to the discs 37 and 38 so that the distance between the discs and the adjacent end of the hopper allow only a single sheet to be extracted upon each revolution of the discs.

This mechanism 51 includes the knurled screw-threaded member 52 which engages a shutter 53 which is adjustable by virtue of the screw-threaded member toward and away from the end 54 of the plate 50 and thereby provides variable means for regulating the distance between an edge of the shutter and the stationary block of bar 62.

A means is provided for jogging the stock contained in the hopper to assist in feeding the stock from the hopper. It may be here stated that this last mentioned structure is not absolutely essential to the operation of

the device as in many instances, it may be entirely eliminated. This jogger and feed is most clearly shown in Fig. 3 and includes a lever 55 pivoted at 56 to the main frame 5 element or plate 57 in which the discs 37 and 38 may be also journaled. The end 58 of the lever 55 extends into the path of rotation of the pin 59, which extends from one face of feed roller 21. The opposite end of the lever 55 has a rod 60 connected at 61 to the lever 55, and this rod 60 rides upon the block 62 supported by the frame element 57. It will be evident that when the pin 59 engages the end 58 of the lever 55, the rod or bar 60 will have a slight endwise and reciprocal motion imparted to it which will assist in jogging the material contained in the hopper and lift the rear edge of the stock so that the resilient segments of the discs 20 37 and 38 may pass said edge and engage the under face of the stock adjacent the forward edge thereof which will prevent buckling of the stock and assist in feeding said stock from the pile contained in the hopper.

25 From the foregoing description of the invention, it is manifest that an extremely simple mechanism is provided for successfully extracting a commodity from the hopper and that the mechanism includes a rotatable 30 member having an element which intermittently rotates into and out of the path of the commodity contained in the hopper, which by virtue of the resilient character of said element will frictionally engage the commodity and cause its extraction from the hopper. It is further evident that the mechanism includes two discs or similar elements which are oppositely rotatable, each of which is provided with means for frictionally en- 35 gaging the commodity and in which said discs rotate in synchronism and cause the resilient elements to intermittently and simultaneously engage the commodity. It is further manifest that the remaining portion 40 of the discs provides means for maintaining the remaining articles in the hopper.

45 Having thus described the invention, what I claim and desire to cover by Letters Patent is:

- 50 1. In a feeding device for feeding stock from a stack, the combination of rotatable means for successively feeding said stock from said stack, and means for elevating one portion of said stack out of the plane of rotation of said feeding means and relatively to another portion and thereby arrange a portion of the stack to allow said feeding means to engage said last mentioned portion of said stock to feed a sheet from said stack.
- 55 2. In a feeding device for feeding sheet stock from a stack, the combination of means for engaging said stock and feeding said stock from said stack, said means being rotatable into and out of the plane of the lowest sheet of the stack, and means for

moving a portion of the lowermost sheet of said stack out of the plane of rotation of said feeding means and thereby allow said feeding means to engage with a portion thereof located in said plane, said rotatable means being movable into engagement with said last mentioned portion of said sheet to extract a sheet from said stack. 70

3. In a feeding device for feeding paper stock to a printing press, the combination of a hopper for the stock and a pair of oppositely rotatable elements arranged at the open end of the hopper having resilient means for frictionally engaging the stock, said means providing means of increasing frictional intensity and providing means for successively feeding stock from the hopper. 75

4. In a feeding device for feeding paper stock to a printing press, the combination of a hopper for the stock and a pair of oppositely rotatable discs having segments providing frictional means for engaging the stock and successively feeding the stock from the hopper. 80

5. In a feeding device for feeding paper stock to a printing press, the combination of a hopper for the stock and a rotatable disc having a segmental portion providing frictional means providing means for engaging the stock and successively feeding the stock 90 from the hopper. 95

6. In a feeding device for feeding paper stock to a printing press, the combination of a hopper for the stock and a rotatable element having means for frictionally engaging the stock, said means being intermittently rotatable into and out of the plane of the hopper and providing means of increasing frictional intensity. 100

7. In a feeding device for feeding paper stock to a printing press, the combination of a hopper for the stock and a pair of rotatable discs each having a resilient element providing frictional means intermittently rotatable in synchronism into and out of the plane of the hopper. 110

8. In a feeding device for feeding paper stock to a printing press, the combination of a hopper for the stock and a pair of oppositely rotatable elements having means for frictionally engaging the stock and providing means of increasing frictional intensity, said means being movable in synchronism into and out of engagement with the stock contained in the hopper. 115

9. In a feeding device for feeding paper stock to a printing press, the combination of a hopper for the stock and a horizontally arranged rotatable element having portions rotatable into and out of the path of movement of the stock contained in the hopper, one of said portions providing means for holding the stock within the hopper and the other providing frictional means for extracting the stock from the hopper, said last mentioned 125 130

portion being angular and having a vertex of the angle arranged to initially engage said stock.

10. In a feeding device for feeding paper stock to a printing press, the combination of a hopper for the stock, a pair of oppositely rotatable discs each having a wedge shaped section providing means for frictionally engaging said stock to successively extract said

10 stock from the hopper.

In witness whereof, I hereunto subscribe my name this 10th day of January, A. D., 1930.
